UNITED STATES PATENT OFFICE.

RICHARD T. ROSS, OF BROOKLYN, NEW YORK.

NECKTIE HOLDER.

Application filed July 27, 1925. Serial No. 46,328.

This invention relates to necktie holders and it consists in the novel features herein-after described and claimed.

An object of the invention is to provide a necktie holder of simple and durable structure and having its parts and features so arranged with relation to each other that the tie with its knot is held in proper shape and position upon the frame of the holder and may be easily and quickly applied to the collar and collar button without requiring the wearer to go through the operation of tying and untying the ribbon strips of the tie during the application of the tie to the collar or the removal of the tie therefrom. While the holder is especially designed to be used in conjunction with a tie generally known as a four-in-hand, it may be used conveniently and economically in conjunction with other forms of ties.

A further object of the invention is to provide means in conjunction with a holder of the character stated for properly holding the tie at an adjusted or desired position with relation to the collar irrespective of the distance of the collar button with relation to the lower edge of the neck band of the collar. That is to say, the device is provided with an attaching means which may be adjusted with relation to the frame of the holder and whereby the tie may be applied to collars mounted upon different shirts and in which the distance from the collar button holes in the neck band to the lower edge of the neck band varies.

A still further object of the invention is to provide in a tie holder a frame consisting of arm portions connected together by an intermediately disposed downwardly curved bowed portion and to which is joined a stem whereby the side or end parts of the bowed portion will hold the knot of the tie in proper shape.

Other objects of the invention will be made manifest as the description thereof progresses.

In the accompanying drawings:

Figure 1 is a perspective view of the tie holder indicating in dotted lines the tie applied thereto,

Figure 2 is a side edge elevational view of the tie holder,

Figure 3 is a perspective view indicating the manner in which the tie is applied to the tie holder, and

Figure 4 is a fragmentary sectional view

of the intermediate portion of the tie holder and indicating in dotted lines the necktie applied thereto.

The frame of the tie holder includes arm portions 1 which are disposed at an angle with relation to each other and which are provided at their outer ends with crossheads 2. The crossheads 2 carry outstanding spaced prongs 3. A downwardly bowed portion 4 is provided and the bowed portion 4 carries at a point midway between its ends a downwardly disposed stem 5. The stem 5 is curved longitudinally and is wedge shape and with its pointed end downwardly disposed. The stem 5 is provided in the vicinity of its lower end with a slot 6. A ring 7 is slidably mounted on the stem 5 and may frictionally engage the upper portion thereof. A tape 8 is connected at one end with the ring 7 and extends down along the stem 5. Said tape is threaded through the slot 6 and carried around the lower pointed end of the stem 5 and carries at its other end a hook 9 which may be engaged with the shank of a collar button 10 in a manner as best indicated in Figure 4 of the drawings.

The necktie which is applied to the holder is indicated at 11. In applying the necktie to the holder one set of the prongs 3 is engaged through the side of the tie at a point between the ends thereof and the tie is carried along one arm 1 of the frame and around the curved bowed portion 4 and stem 5 and then up along the other arm and engaged with the other set of prongs, as shown in Figure 3 of the drawings. The end portions of the tie are then wrapped around that part of the tie which is wound about the stem and the bowed portion 4, and the knot is formed in a usual manner.

In order to connect the tie and the tie holder with the collar and shirt, the hook 9 is first passed over the shank of the collar button 10 and then one arm portion 1 is inserted under one end of the collar and finally the other arm portion 1 is inserted under the opposite end of the collar. Thus the tie holder and the tie are applied to the collar and shirt. Should variation occur in the distance between the collar button holes and the lower edge of the collar band of the shirt, the ring 7 may be adjusted along the stem 5 whereby the tape 8 is lengthened or shortened with respect to that portion thereof which projects beyond the end of the stem 5 and consequently the

said tape may be adjusted longitudinally to compensate for any variation in distance between the collar button holes and the lower edge of the neck band of the collar in order to properly hold the frame and the tie in position with relation to the collar and the bosom of the shirt.

From the foregoing description, taken in conjunction with the accompanying drawings, it will be seen that means are provided for properly holding the tie in shape, for holding the knot of the tie in proper form, and also for holding the tie in proper position with relation to the collar and bosom of the shirt notwithstanding the fact that there may be variation in different shirts in the distance between the collar button holes and the lower edges of the neck bands.

The sleeve 12 is slidably mounted upon the tape 8 and may slip over the end of the stem portion 5 and frictionally engage the stem portion and clamp the tape at an adjusted position upon the stem portion in a manner as most clearly shown in Figure 4 of the drawing. Thus it is seen that means are provided for holding the tape at an adjusted position with relation to the stem.

Having described the invention, what is claimed is:

- 38 1. A necktie holder comprising a frame having a pair of arm portions and an intermediate stem portion, said arms being bowed downwardly at the point of connection of said stem portion thereto so as to 35 form a V-shaped portion for properly forming a knot when a tie is arranged about said V-shaped portion and said stem portion.
2. A tie holder comprising a frame having arm portions to be disposed between the 40 folds of a collar and an intermediate stem portion around which the knot of a tie may

be arranged, a ring slidably mounted upon said stem portion, a tape connected to said ring, means for adjustably holding said tape to said stem, and means carried by said tape 45 for engagement over a collar button.

3. A tie holder comprising a frame having arm portions to be disposed between the folds of a collar and an intermediate stem portion around which the knot of a tie may 50 be formed, and outwardly extending prongs arranged upon the ends of said arm portions for engaging into a tie arranged about said arm for preventing slipping movement of the tie on the arms.

4. A tie holder comprising a frame having arm portions to be disposed between the folds of a collar and an intermediate stem portion around which the knot of a tie may 55 be formed, the stem portion being provided with a slot, a ring slidably mounted upon the stem portion, a tape connected with the ring and threaded through the slot, and a hook carried by the tape for engagement over a collar button.

5. A tie holder comprising a frame having arm portions to be disposed between the folds of a collar, and a longitudinally curved wedge shape stem portion around which the knot of a tie may be disposed, said stem portion 60 having a slot therein, a ring slidably mounted upon the stem portion, a tape connected with the ring and threaded through the slot, a hook attached to said tape for engagement over a collar button, and a sleeve 65 slidably mounted upon the tape and adapted to engage over and around the stem portion for adjustably connecting said tape to said stem portion.

In testimony whereof, I have affixed my 70 signature.

RICHARD T. ROSS.
